UNITED STATES PATENT OFFICE.

HERMAN H. WOLTER, OF MERIDEN, CONNECTICUT, ASSIGNOR TO THE MILLER COMPANY, OF NEW YORK, N. Y., A CORPORATION OF CONNECTICUT.

DESIGN FOR A LIGHTING-FIXTURE PAN.

Application filed February 27, 1924. Serial No. 8,764. Term of patent 3½ years.

To all whom it may concern:

Be it known that I, HERMAN H. WOLTER, a citizen of the United States, residing at Meriden, in the county of New Haven and State of Connecticut, have invented a new, original, and ornamental Design for a Lighting-Fixture Pan, of which the following is a specification, reference being had to the accompanying drawing, forming a part thereof.

Figure 1 is a perspective view of the

lighting fixture pan made according to my design.

Fig. 2 is a plan view of the design shown in Fig. 1 with only one-half of the design completed, the remaining half being a repeat of the part more fully shown.

I claim:

The ornamental design for a lighting fixture pan, as shown.

HERMAN H. WOLTER.
